UNITED STATES PATENT OFFICE.

JOHN H. NEEL, OF LOS ANGELES, CALIFORNIA.

THERAPEUTIC APPARATUS.

1,120,964.

Specification of Letters Patent. Patented Dec. 15, 1914.

Application filed June 3, 1913. Serial No. 771,427.

To all whom it may concern:

Be it known that I, JOHN H. NEEL, a citizen of the United States, residing at Los Angeles, in the county of Los Angeles and 5 State of California, have invented new and useful Improvements in Therapeutic Apparatus, of which the following is a specification.

This invention relates to therapeutic apparatus, and the principal object is to provide a magnetic device in which a person may be subjected to the lines of force formed between a series of magnets.

It is also an object to provide means for 10 adjusting the relation of the magnets so that the latter may be arranged to accommodate persons of different size.

It is a further object to provide a magnetic device of the above character on a movable base so that it can be readily adjusted.

In the drawings accompanying this specification and forming therewith the application for Letters Patent: Figure 1 is a front elevation of the device, showing the diagrammatic arrangement of the wiring connected therewith. Fig. 2 is a plan view of the structure showing the adjusted position in dotted lines. Fig. 3 is a perspective detail of one of the magnetic windings.

More specifically in the drawings, 5 designates a base formed of two parts acting as a floor upon which a person may stand, the lower portion 6 of this floor being provided with a plurality of supporting castors 7. This lower plate forming the floor is recessed or rabbeted for a greater portion of its surface and is adapted to receive a movable section 8 which is provided with a longitudinally disposed slot 9 which extends from its inner edge outward and is adapted to form a sliding connection with the bolt 10 which is threaded into the lower section 6 at a suitable point so that the section of the floor 8 may be slidably adjusted 40 in relation to the plate 6. Mounted upon the unrecessed upper surface of the plate 6 is an upright standard 11 preferably located near the outer edge of the plate and formed either of soft iron or built up of laminated

50 strips having a plurality of extensions 12, 14 and 15, which are preferably formed as cubical bodies. Suitable brackets 16 secure and support this standard in relation to the plates 6 and the oppositely disposed end of 55 the plate 8 is similarly provided with brackets 17 which support and hold in the same

relation on this plate 8 a standard 18 similar to the standard 11 and having its cubical extensions in the same plane and registering with those on the standard 11. Mounted on 60 each one of these cubical extensions and acting as a support therefor are winding drums 19 having a winding 20 thereon of suitable insulated wire, the central aperture through these drums having the same configuration 65 as the cubical extensions so that they fit thereon, and the free ends of the wire forming the coils may be joined to the wiring of the adjacent coils to form a series of independent electric magnets. For convenience 70 in description each one of these coils as shown in Fig. 1 is designated 21, 22 and 23 being mounted on the extensions on the standard 11 with their windings joined in series, the upper coil 23 on the standard 11 75 being joined by the wire 24 to the coil 25 on the upper extension of the standard 18, this coil 25 being connected in series with the coils 26 and 27 on the next succeeding extensions on the core 18. The wire 28 connects the coil 27 to a switch 30, the wire 29 connecting the coil 21 to the oppositely disposed connection on the same double pole switch. The other two connections on this switch are connected by wires 31 and 32 to 80 a direct current generator 33 having a shunt wiring 34 with a rheostat 35 connected in the generator winding circuit.

The series of coils on one standard are preferably arranged so that the polarities 90 are alternated as shown in the drawings, the oppositely disposed coil affecting the cubical core being so arranged that its magnetic pole is of the opposite polarity, and so on in succession so that the lines of force may 95 travel from one pole to the oppositely disposed pole, and a patient standing on the floor intermediate of these poles will be bathed and saturated with the magnetic influence. As clearly shown in Fig. 2 the plate 100 8 and its standard 18 may be adjusted longitudinally to accomodate any variations desired to bring the magnet poles closer together or disposed at a greater distance as found necessary.

What I claim is:

1. A therapeutic device of the character described, comprising a base formed of a plurality of overlapping members, a slot being formed in one of said members, a screw 110 supported in the other of said members to adjust said members in relation to each

other, an iron standard mounted on each of said members, having extensions formed thereon and adapted to register with extensions on the oppositely disposed standard, 5 coils of wire mounted on each of said extensions, and means to electrically energize said coils so that magnetic poles will be formed by the flow of electric current through said coils so that lines of magnetic force will extend across the area between the opposed poles.

2. A magnetic device of the character described, comprising a movable base, a plurality of upright standards mounted on said base having extensions outwardly disposed therefrom and registering on the oppositely disposed standards, coils of wire mounted on said extensions, means to adjust said standards to and away from each other and 15 means to connect said coils to a source of electrical energy, whereby said standards are converted into electro-magnets and the lines of force are distributed across the interval between said supporting extensions.

3. A magnetic device of the character described, comprising a base formed of a plurality of members, means to adjust said members in relation to each other, a metallic standard mounted on each of said members, cubical extensions formed on said metallic standard and adapted to register with extensions on the oppositely disposed standard, coils of wire mounted on each of said extensions, and means to connect said coils so that the magnetic poles formed by the flow of electric current through said coils will be oppositely disposed on each standard and the oppositely disposed extensions so that lines of magnetic force will extend across the area between the opposed poles. 35

In witness that I claim the foregoing I have hereunto subscribed my name this 24th day of May, 1913.

J. H. NEEL.
